UNITED STATES PATENT OFFICE.

BURT S. HARRISON, OF CHICAGO, ILLINOIS, ASSIGNOR TO DRYING SYSTEMS, INC., OF CHICAGO, ILLINOIS, A CORPORATION OF ILLINOIS.

VENEER DRIER.

Application filed November 12, 1924. Serial No. 749,392.

This invention relates to drying apparatus generally, but more particularly to a suitable means for conveying sheet material, such as veneer, through a drying room. The purpose of the invention is to so support the veneer while being conveyed through the drying room that the air has freedom of access to both sides of the veneer, and the latter is prevented from warping during the drying process. The construction illustrated, and by means of which the invention is practiced, is light and requires comparatively little motion and power in its operation.

The objects of the invention are accomplished by a construction as illustrated in the drawings, wherein—

Figure 1 is a fragmentary plan view of the conveyer with the surrounding walls shown in section.

Figure 2 is a transverse sectional view taken on the line 2—2 of Figure 1.

Figure 3 is a fragmentary side view of the conveyer.

Figures 4 and 5 are details illustrating the method of resiliently supporting the upper sets of veneer engaging bars.

The construction illustrated consists essentially in a plurality of horizontally disposed bars of suitable operating means, whereby opposed sets of said bars are caused to alternately grip the veneer passed between said bars, and slowly and continuously carry the veneer through the drying room. These horizontally disposed sets of bars are carried on frames, one frame being provided for each set of bars, and these frames in turn are supported by elements adapted to raise and lower the said frames as required for gripping material operated upon, and means are also provided for reciprocating the frames in the direction of length of the drying room for the purpose of transporting the material.

This construction, as illustrated in the drawings, shows four sets of horizontally disposed bars numbered 1, 2, 3 and 4. The set of bars 1 is carried by brackets 5 extending upwardly from cross members 6 of the frame 7. This frame 7 carries casters 8 resting on rails 9. Above the bars 1 are a set of bars 3, loosely or resiliently supported in brackets 10 carried by cross bars 11 of the frame 12. This frame is also sup-

ported by casters 13 resting upon rails 14. 55 The rails 9 and 14 are carried by bell crank levers or rocker arms 15, arranged to rock on transverse shafts 16. A slight reciprocation of one of the rails 9 or 14 therefore results in causing the rail to move in an arc 60 around the shaft 16 and through the bell crank lever 15, imparting a similar motion to the other rail. Accordingly, while the pair of rails 9 and the frame supported thereon may rise slightly due to this arc 65 motion, the pair of rails 14 and the frame 8 supported thereon will at the same time lower. On the reverse stroke of the rail an opposite motion is imparted to the frames, frame 7 lowering while frame 12 rises slightly. 70 In this way the two coating sets of bars 1 and 3 are caused to alternately come together and grip the veneer and then move apart, releasing the veneer.

This motion is imparted to the rails 9 75 and 14 by the rotary shaft 32 extending transversely of the drier at one end thereof. This shaft carries eccentrics 17 or other similar means for regularly reciprocating the rails 9 and 14 in order to impart the 80 desired vertical motion of the frames 7 and 12. For this purpose the eccentric 17 is connected by a pitman 18 with one of the rails. Shaft 32 is continuously driven by a belt driven pulley 19. It also carries an 85 eccentric 20 for imparting a similar motion to the rails 21 and 22. These rails are also supported on bell cranks 23, and likewise support frames 24 and 25, which through the brackets 26 and 27 support the two 90 sets of rails 2 and 4. The eccentric 20 is similar to the eccentric 17, but is set one hundred and eighty degrees apart from the latter so that when the sets of bars 1 and 3 move toward gripping relation the sets 95 of bars 2 and 4 will move away from gripping relation. Shaft 32 also carries means, such as the eccentrics 28, for reciprocating the frames 7, 12, 24 and 25. While the pair of frames 7 and 12 are moving on the 100 forward stroke, the frames 24 and 25 will be caused to move rearwardly. The result is that the veneer or other sheet material while between the bars 1 and 3 and 2 and 4 will be alternately gripped and carried forward by the opposed bars 1 and 3 and 2 and 4. The pressure between the two opposed sets of bars is determined by either 105

the weight of the upper bars or spring pressure on these bars. The upper bars are preferably supported in the brackets 10 and 27, as illustrated in Figures 4 and 5. These 5 brackets are provided with vertical slots 29, through which are passed the bars 3 and 4, so as to be free to move relatively of the brackets in a vertical direction. The brackets carry pins 30 extending below pins 31 10 on the bars. When the bars 3 and 4 come to rest upon the veneer any excess motion of their supports is compensated for by the slots 29.

In the operation of the device, the motor 15 is continuously driven, and through the eccentrics on the driven shaft 32 causes the desired arc motion of the rails 9, 14, 21 and 22 in order to raise and lower the frames supported thereon as required for 20 alternately bringing the opposed pairs of bars 1 and 3 and 2 and 4 into gripping relation with the veneer. As soon as two sets of the bars so grip the veneer the corresponding frames are drawn forward, 25 and then when these bars release the veneer the remaining sets of bars 2 and 4 grip the veneer and are carried forward by the motion imparted to their respective frames, while the frames 7 and 12 are traveling 30 through their return stroke.

The construction shown is comparatively light and substantially counter-balanced, the weight of frame 7 and frame 24 and parts carried thereon being substantially the 35 same as the weight of frames 12 and 25 and parts carried thereby. It therefore requires little power to rock the bell cranks 15 together with the rails and frames supported thereon. The longitudinal reciprocation of the frames also does not require 40 much power, since the frames are light and roll along the supporting tracks. The entire structure is housed, as indicated in the drawing, as required for confining the air 45 circulated around the material operated upon.

The veneer gripping elements have been described as bars, although it will be understood that rods or even light wires or cords 50 will be substituted for the bars, depending

upon the nature of the material carried by the conveyer.

Although but one specific embodiment of this invention has been herein shown and described, it will be understood that numerous details of the construction shown may be altered or omitted without departing from the spirit of this invention as defined by the following claims.

I claim:

1. A machine of the class described suitable for conveying sheet material, comprising opposed sets of horizontally disposed bars, suitable supporting and operating means for said bars whereby two opposed sets thereof are caused to move toward each other and engage the material there between and then move in a longitudinal direction to carry the material forward while at the same time other sets of opposed bars move away from the material and are shifted rearwardly into position to again engage the material and carry it forward, said supporting means comprising frames and tracks upon which said frames are slid, means for reciprocating said frames along said tracks, and means for imparting an up and down motion to the tracks.

2. A machine of the class described suitable for conveying sheet material, comprising opposed sets of horizontally disposed bars, suitable supporting and operating means for said bars whereby two opposed sets thereof are caused to move toward each other and engage the material there between and then move in a longitudinal direction to carry the material forward while at the same time other sets of opposed bars move away from the material and are shifted rearwardly into position to again engage the material and carry it forward, said supporting means comprising frames and tracks upon which said frames are slid, means for reciprocating said frames along said tracks, means for imparting an up and down motion to the tracks, and rocker arms for supporting said tracks.

Signed at Chicago this 4th day of November, 1924.

BURT S. HARRISON.
